FLORAL RACK

Clarence J. White, Peoria, Ill.

Application May 8, 1950, Serial No. 160,622

10 Claims. (Cl. 248—27.8)

1

This invention relates to improvements in floral racks of the collapsible type now much used for the display of floral pieces. More particularly the invention pertains to means for automatically swinging the prongs of a collapsible floral rack to open or closed positions.

In such racks as illustrated, for example, in U. S. Patent No. 2,115,693, issued me on April 26, 1938, a series of prongs are pivotally supported on a lazy-tongs structure which forms the "face" of the rack, these prongs being swung to closed positions adjacent said face of the rack by special operating means separate from the lazy-tongs, said prongs by gravity moving to open positions when released by said operating means.

The present invention, while mounting the prongs pivotally on the lazy-tongs as before, has as its object, and by contrast, the provision of operating means also on the lazy tongs by which to both positively open and close said prongs, said means also permanently holding the prongs against sidewise tilting without respect to the positions of swing of the members of said lazy-tongs relative to each other.

To further distinguish from known rack structure where the prongs are pivoted to a lazy-tongs and are controlled by means separate from the latter, it is to be stated that the prongs in the present instance are operated by the crossed members of the lazy-tongs themselves in the swinging movements thereof.

In order that the invention may be fully understood in all of its details, the appended drawing is provided forming part hereof.

Fig. 1 is a front elevation of a part of a collapsible floral rack showing prongs thereon according to my invention.

Figs. 2 and 3 are front elevations of parts of two lazy-tongs members in two different positions of spread, a prong included in my invention being shown in each.

Fig. 4 is a side elevation of the parts illustrated in Figs. 2 and 3 but with parts thereof overlying and aligned with each other, a finger or prong thereon lying in close relation thereto.

Fig. 5 is a vertical longitudinal section of the invention as illustrated in Fig. 4, but much enlarged.

Fig. 6 shows in perspective part of a pivot member illustrated in Fig. 5.

Fig. 7 is a horizontal transverse section of the structure of Fig. 5 produced on the same scale.

Fig. 8 is a plan or face view of a cam plate entering into the invention produced on the same scale as Figs. 5 and 7.

2

Fig. 9 is a perspective view of the cam plate shown in Fig. 8, a portion of the cam plate being broken away to show the position of a pin on the back thereof.

5 Fig. 10 is a plan or face view of a plate involved in the structure of the foregoing figures.

Figs. 11 and 12 are elevations of two lazy-tong members in different positions of adjustment together with a certain operating member, Fig. 11 10 being produced on line 11 of Fig. 4, and

Fig. 13 is an elevation of a pair of lazy-tong members separate from other parts, this figure showing certain apertures and their relations to each other.

15 In accordance with the invention, the floral display prongs are actuated between open and closed position by expansion and contraction of the lazy-tongs of the rack, the prongs being wholly supported by the members of the lazy-tongs. It is to be understood that the parts in all of the figures of the drawing, except Figs. 4, 5, 6, 7, and 9, are shown as they appear in viewing the rack from the front thereof. Reference numerals 1 and 2 indicate a front and rear bar, 20 respectively, of the rack, these being pivotally mounted to swing across each other in the well known manner.

At their points of crossing, the bars, 1 and 2 receive a member answering as a pivot pin upon

30 which the bars may rock, said member comprising a head 3 having a slot 4 in the outer face thereof, a cylindrical portion 5 extending from its opposite face and terminating in a threaded stem 6 of reduced diameter. As shown in Fig. 6

35 the portion 5 at the root of the said stem is reduced at opposite sides forming a flat portion 7 substantially equal to the diameter of the said stem 6 and thus providing shoulders 8. In passing, it is to be said that as to the head 3,

40 the named slot 4 is of a depth, only, as to leave a wall 3' appearing in Figs. 5 and 7 from which the said portion 5 extends. A cavity 9 opens through said wall 3' and into the said portion 5 within which lies an expansible coil spring 10.

45 Lying within the slot 4 is one end of a floral piece supporting prong 11, a pin 12 extending through the head and prong serving as a pivot for the latter, the said spring bottoming in both the cavity 9 and said prong. Thus, the prong 11 may pivot

50 about the pin 12 from a position parallel with the plane of the front bar 1 outwardly to an extended position, the latter position being indicated by the dotted lines in Fig. 5. The spring 10 normally urges the prong to its outward position.

55 During the pivotal motion of the prong, the prong

is prevented from tilting from side to side relative to the head 3, since the pin 12 is securely mounted in the head 3.

In Figs. 8 and 9 a cam-plate 13 is illustrated, which as shown in Figs. 5 and 7 abut the wall 3' of the head 3, as permitted by a central hole 13' of said plate to receive the portion 5 through it. This said plate 13 carries a cam 14 at one face thereof, which as shown in Fig. 5 is in position to receive the heel of the prong 11 upon it. Extending from the opposite face of the cam-plate is a pin 15 which enters an aperture 1' of the bar 1, Fig. 13, and as shown in Fig. 7, which bar by a hole 12 slips over the portion 5 and abuts the cam-plate 13.

Next in progression along and upon the member 3, 5, 6, following the bar 1, is a member in the form of a slotted plate 16 shown in Figs. 4, 5, 11, and 12. In the latter two figures this plate is shown in position between the front and rear bars 1 and 2, respectively. It is observed that said plate 16 has a slot 17 therethrough extending the greater part of its diameter measured in one direction, while at each side of said slot is a shorter slot 18 and 19, respectively, extending radially at right angles to said slot 17 and approximately at the middle of the said greatest diameter of the plate.

In Fig. 5 it will be noted that the flat portion 7 is positioned within the slot 17 of the said plate 16, the slot 17 having such that the plate is prevented from rotating about said flat portion but may shift laterally thereon.

It will also be noted that the combined thickness of the cam-plate, bar 1, and plate 16, equals the distance from the head 3 to the outer surface of the flat portion 7 at the root of the threaded stem 6, and that the bar 1 may rock on the portion 5, though the plate 16 cannot rock or rotate, but can only shift in a lateral direction.

The bar 2, Fig. 13, is provided with a hole 2' near a longitudinal edge thereof, and also has a hole 2" at its center and which centers with the hole 12 of the bar 1 as shown, but is of a smaller diameter to receive the threaded stem 6, the bar 2 being positioned on the latter to abut the slotted plate 16, and abutting the end of the flat portion 7, being free to rock on said stem. Placed upon the stem, also, to follow said bar 2 is a plate 20 shown in Fig. 10. This plate has a central hole 20' to receive through it the said stem 6, and also having a pin 20" near its edge and extending from one side thereof, see Fig. 7, designed to engage in the hole 2' of the bar 2 and also to engage in the slot 19 of the plate 16. It is equally true that the pin 15 of the cam-plate 13 extends through the hole 1' of the bar 1 and into the slot 18 of the plate 16, the pins 15 and 20" lying at opposite sides of the portion 5 and the said stem 6 as shown in Fig. 7. Thus, the pins answer as linkage between the bars 1 and 2 and the plate 16.

Finally, a washer 21 may be slipped upon the shank 6 against the plate 20 followed, for example, by a "lock-washer" 22 and a nut 23 to complete the assembly. The operation of the assembly just described is such that, whether the lazy-tongs is collapsed, with the bars 1 and 2 thereof aligned, as seen in Fig. 12, or expanded, with the bars 1 and 2 rocked out of alignment, as seen in Figs. 1 and 11, the prong 11 will not be tilted sidewise. To insure this result the slotted plate 16 is provided together with the pins 15 and 20" of the bars 1 and 2, respectively.

As already stated, the said plate 16 cannot

rotate because the slot 17 thereof is engaged over the flat portion 7, and the slot 17 therein at all times parallels the longest measurement of said prong 11 since the flattened portion 7 parallels the latter as a part of the slotted head 3.

The said pins 15 and 20" lie at opposite sides of the axis of the pivot pin comprising portions 5 and 6 and are equally spaced therefrom, being so placed on the bars carrying them that, in the swing of said bars about said center, they move in unison through equal arcs. When the bars are aligned with each other, as in Fig. 12, the pins 15 and 20" are at their lowest position with respect to the pivot pin, and lie below the same, the plate 16 also being at its lowest position as permitted by the slot 17, the prong being closed. As the bars are spread, however, as in Fig. 11, the pins thereof lie in the higher position in respect to the said unit portion. Since moving in unison the same distance at all times, the plate being non-rotatable, the prong 11 must hold the same relation as that of said plate, said prong at this time being open, or widely spaced outwardly from the bars.

The spring 10 is always under compression and moves the prong away from the planes of the bars 1, when the latter are spread as in Fig. 3, at which time the cam 14 has been moved from beneath the heel of the prong. In Figs. 2 and 5, where the cam lies beneath the heel of the prong, the prong is closed toward the bars placing the spring, incidentally, under greater compression.

The plate 16, the cam-plate 13, and the plate 20 together may be termed a linkage as the parts assisting in the operation of the device in connection with the bars 1, 2 as the operating members.

By such a structure as described and shown, or its equivalent, the lazy-tongs of a folding rack carry the prong as heretofore, of course, but further, the lazy-tongs carries the means for complete prong control without the necessity of use of other parts of the rack as is now commonly practiced. Otherwise stated, the prong actuating means is wholly within and of the lazy-tongs itself.

I claim:

1. In combination, a pair of bars of a floral rack crossed upon each other, a member serving as a pivot for said bars at the place of crossing thereof, a prong pivoted on said member transversely thereof, said prong being swingable therewith, and adapted to swing in a plane perpendicular to the planes of swing of said bars, a second member operatively engaging the first member and held from rotating with respect thereto, while shiftable laterally with respect to said member in a direction paralleling the longest measurement of the said prong, and two linkages having positions between and engaging said bars and said second member, the engagement of the linkages with the bars being spaced at opposite sides of the pivotal point of the same, and their engagement with said second member being placed at opposite sides of the longest axis of said first member, the said arms in their swing relative to each other adapted through said linkages to impart lateral shift to said second member.
2. The combination with two crossed bars of a collapsible floral rack and a member extending through both bars at their places of crossing, and upon and about which said bars swing in parallel planes, and a prong pivoted on the member to swing in a plane at right angles to the planes of

swing of said bars, of a separate mounted member engaging the first member adapted to swing with said prong and free to shift laterally with respect to said first member in a plane substantially paralleling the said planes of swing of said bars, and paralleling the longest measurement of the prong, and a linkage part of which extend from each bar and operated thereby, both linkages operatively engaging the said mounted member adapted in the swing of the bars relative to each other to impart lateral shift to the same.

3. The combination with two crossed bars of a collapsible floral rack and a member extending through both bars at their places of crossing, and upon and about which said bars swing in parallel planes, and a prong pivoted on the member to swing in a plane at right angles to the planes of swing of said bars, of a separate mounted member engaging the first member adapted to swing with said prong and free to shift laterally with respect to said first member in a plane substantially paralleling the said planes of swing of said bars, and paralleling the longest measurement of the prong, and a linkage part of which extend from each bar and operated thereby, the linkages being separately engaged with the mounted member at positions opposite each other and at opposite sides of the position of engagement of said mounted member with the said first member, and the places of linkages at the said bars being equidistant from the pivoting position of said bars.

4. In combination, a pair of bars of a floral rack crossed one upon the other, a member extending through the bars at the place of crossing thereof serving as a pivot for the same, a prong pivoted on the member adapted to rotate therewith and swingable in a plane at right angles to the direction of swing of said bars, a second member engaging the first member adapted to rotate therewith and capable of shifting in a lateral direction paralleling the longest measurement of said prong, and two linkages each engaging a bar of said pair of bars and engaging said second member at opposite sides of the axis of said first member, the said linkages at said bars having separate positions spaced equally from the position about which the bars swing.

5. In combination, a pair of bars of a floral rack crossed one upon another, a member extending through the bars at the place of crossing thereof serving as a pivot about which said bars swing, a prong pivoted on the member to rotate therewith and swingable in a plane at right angles to the direction of swing of said bars, a second member lying between said bars and engaging the first member and held from rotating with respect to the latter, said second member being shiftable with respect to said first member in a lateral direction substantially paralleling the direction of swing of said bars, means extending from each bar spaced equally from the center of swing of the same, each said means being operatively engaged with the said second member, the places of engagement with the latter being equally spaced laterally from the axis of the first said member.

6. In combination, a pair of bars of a floral rack crossed one upon another, a member extending through the bars at the place of crossing thereof serving as a pivot about which said bars swing, a prong pivoted on the member to rotate therewith and swingable in a plane at right angles to the direction of swing of said bars, and said member having a portion provided with a flat face paralleling the longest measurement of the said

prong, a second member consisting of a plate having a slot thereacross to receive the said portion thereto, said face preventing rotation of the two members relatively, and said slot permitting a lateral shifting of the said second member relative to the first member, and said second member having a slot therein at each side of the position of the first named slot and lying substantially at right angles to the same, each of the crossed bars having a pin extending therefrom, the pins each being separately engageable in a second named slot of the said second member.

7. In combination, a pair of bars of a floral rack crossing one upon the other, a member extending through the bars at the place of crossing thereof serving as a pivot upon which said bars swing, a prong pivoted on one end of the member to swing in a plane at right angles to the planes of swing of said bars and held to rotate with said member, a plate mounted on the said member distant from said prong and having a cam-portion engageable beneath one end of the latter, a pin extending from the surface of the plate most distant from the prong, one of the named crossed bars abutting said plate and having a hole therethrough to receive said pin, a second plate on said member, the said second plate having a slot thereacross, and said member having a flat face on a part thereof paralleling the longest measurement of the named prong, said face abutting a wall of said slot of the plate preventing rotary movement thereof with respect to said member, the said slot permitting a lateral shifting movement of the plate with respect to the said member and said second plate also having a slot at each side of the first named slot, the same lying substantially at right angles to the first named slot, the other bar of the two named bars abutting the second named plate and provided with a hole therethrough, a third plate carried by the member and abutting the last named bar, a pin extending from the said third plate through the said hole in said other bar and also extending into one of the second named slots of the second named plate, the named pin on the first named plate extending into the other of the second named slots, and means for securing all of the described parts in substantial abutment with each other, the named pins of the first and third named plates lying at opposite sides of the axis about which the bars swing and equally spaced therefrom.

8. In combination, a pair of bars of a lazy-tongs type floral rack crossed one upon the other, a pivot pin having a head and a shank, said shank extending through said bars at their point of crossing and having a flattened portion positioned between said bars; a member positioned between said bars, said member having an elongated slot thereacross and a pair of slots located one on each side of and at right angles to said elongated slot, said elongated slot embracing the flattened portion of said pivot pin to prevent relative rotation between said member and said pivot pin; a pair of linkage pins each extending through one of said bars on one side of said pivot pin and engaging in one of said pair of slots, whereby rocking motion of said bars about said pivot pin is converted to linear motion of said member on the flattened portion of said pivot pin, and a floral piece supporting prong pivoted to the head of said pivot pin to swing in a plane at right angles to the planes of swing of said bars.

9. In combination, a pair of bars of a lazy-

tongs type floral rack crossed one upon the other; a pivot pin having a head and a shank, said shank extending through said bars at their point of crossing and having a flattened portion positioned between said bars; a member positioned between said bars, said member having an elongated slot thereacross and a pair of slots located one on each side of and at right angles to said elongated slot, said elongated slot embracing the flattened portion of said pivot pin to prevent relative rotation between said member and said pivot pin; a pair of linkage pins each extending through one of said bars on one side of said pivot pin and engaging in one of said pair of slots, whereby rocking motion of said bars about said pivot pin is converted to linear motion of said member on the flattened portion of said pivot pin; a floral piece supporting prong pivoted to the head of said pivot pin to swing in a plane at right angles to the planes of swing of said bars, said prong having a heel portion extending beyond the pivot point between said prong and said head, and a cam member mounted on said pivot pin for rotation thereabout, said cam member being connected to one of said linkage pins and having its cam face arranged for engagement under the heel of said prong, during rocking motion of said bars as the rack is collapsed, to pivot said prong into retracted position.

10. In combination, a pair of bars of a lazy-tongs type floral rack crossed one upon the other; a pivot pin having a head and a shank, said

shank extending through said bars at their point of crossing and having a flattened portion positioned between said bars; a member positioned between said bars, said member having an elongated slot thereacross and a pair of slots located one on each side of and at right angles to said elongated slot, said elongated slot embracing the flattened portion of said pivot pin to prevent relative rotation between said member and said pivot pin; a pair of linkage pins each extending through one of said bars on one side of said pivot pin and engaging in one of said pair of slots, whereby rocking motion of said bars about said pivot pin is converted to sliding motion of said member on the flattened portion of said pivot pin; a floral piece supporting prong pivoted to the head of said pivot pin to swing in a plane at right angles to the planes of swing of said bars, said prong having a heel portion extending beyond the pivot point between said prong and said head, and a disc carried by said pivot pin between said head and the adjacent one of said bars and being free to rotate about said pivot pin, said disc being connected to one of said linkage pins and having a cam face arranged for engagement under the heel of said prong, during rocking motion of said bars as the rack is collapsed, to pivot said prong into retracted position.
